[57]

CLAIM

The ornamental design for a plastic tubing connector, substantially as shown and described.

DESCRIPTION

FIG. 1 is a side elevational view of a plastic tubing connector showing my new design;

FIG. 2 is an elevational view taken from one end thereof, the opposite end being the same as the end shown; and

FIG. 3 is a cross sectional view taken on line 3—3 of FIG. 1.

FIG. 1

FIG. 2

FIG. 3
